(57) **CLAIM**

The ornamental design for a top cap for an electric toothbrush handle, as shown and described.

DESCRIPTION

FIG. 1 is an isometric view of an electric toothbrush handle illustrating my new design;

FIG. 2 is a front elevation view thereof;

FIG. 3 is a right-side elevation view thereof;

FIG. 4 is a back elevation view thereof;

FIG. 5 is a left-side elevation view thereof;

FIG. 6 is a top plan view thereof; and,

FIG. 7 is a bottom plan view thereof.

The broken lines in the drawings depict portions of the top cap for an electric toothbrush handle that form no part of the claimed design.
